EXERCISING APPARATUS

George W. Dunham, Westport, Conn.

Application August 5, 1953, Serial No. 372,563

6 Claims. (Cl. 272—58)

The invention relates to exercising apparatus and more particularly to apparatus to assist those who, for various reasons, find it necessary to take what is sometimes called the Berger Exercise.

The Berger Exercise consists in lying on the back with the legs held up substantially vertical for a given period of time. The patient then sits up with the legs hanging over the edge of the couch without touching the floor while the feet and toes are articulated. After this, the patient lies down with the legs stretched out horizontally. The above cycle is then repeated.

According to the present invention, a special couch is provided having special provision for taking the Berger Exercise with a maximum of comfort. Other objects of the invention will be apparent from the description and claims.

In the drawings which illustrate one embodiment of the invention,

Fig. 1 is a perspective of the exercise apparatus, according to the invention, in set up position;

Figs. 2, 3 and 4 show diagrammatically the three main positions of the Berger Exercise, to illustrate how the apparatus is used;

Fig. 5 shows the apparatus folded flat for storage;

Fig. 6 is a detail, taken on the line 6—6 of Fig. 1, illustrating the construction of a leg pivot and of a diagonal brace;

Fig. 7 is a section, on the line 7—7 of Fig. 1, illustrating the adjustment of the upper foot rest;

Fig. 8 is a perspective of a special washer;

Fig. 9 is a section, on the line 9—9 of Fig. 1, illustrating the manner of hinging the lower foot rest; and

Fig. 10 is a section, on the line 10—10 of Fig. 5, illustrating how a strand of webbing is attached to a supporting tubular member.

Referring now to the drawings, the couch comprises in general a couch top 10, legs 11 at the head end of the couch, legs 12 at the foot end, a lower foot rest 14, an upper foot rest 15, and diagonal braces 27. The couch, in general, may be made up of metal tubing, and flexible webbing, such as commonly used in garden furniture.

The couch top 10 comprises a U-shaped frame made up of side rails 16 having extensions 17, with a cross brace 18 at the foot end suitably welded to the rails 16. Webbing, indicated in general by 19, is stretched across the couch, both longitudinally and transversely, in an interwoven configuration. Each end of each web strand is wrapped around the particular tubing to which it is connected and held in place by set screws and washers indicated by 20 (see Fig. 10). The couch top is of such length as to accommodate the trunk and head of the tallest patient for which the couch is designed. The couch legs 11, 12 are long enough to place the couch top 10 above knee height (Fig. 4).

The extensions 17 support a lower "foot" rest 14 in such position as to support the patient's legs or feet as he lies down on the couch, as shown in Fig. 3. A hinge strap 23 (Fig. 9) loosely surrounds the adjacent extension 17

2

so that the foot rest 14 may be raised to permit a patient to walk between the extensions 17 and sit down on the foot of the couch at cross brace 18. The lower foot rest is also adjustable lengthwise of the extensions 17 according to the patient's height.

The legs 11 at the head of the couch are made of a single U-piece pivoted to the insides of the rail 16, as shown. The legs 12 at the foot of the couch have uprights 13 formed into U-shape and pivoted to the outside of the rails 16.

The upper adjustable "foot" rest 15 has a fixed hook 24 (Fig. 7) attached thereto by which the foot rest 15 is slidable on the upright 13. An adjustable hook 25, in the form of a clamp, is provided at the other end of the foot rest 15. A thumb nut 22 is provided for adjusting the clamp 25. It will be understood that by loosening the thumb nut 22, the foot rest 15 may be slid vertically up and down uprights 13, to accommodate the patient's height.

It will be noted from the drawing that the lower foot rest 14 actually contacts the lower leg of the patient and thus indirectly supports the patient's foot; in the claims the term foot rest is intended to cover any rest that supports leg or foot of the patient.

The several pivots for securing the legs to the rails 16 have similar construction. The pivot securing leg 12 to rail 16 is described with reference to Figs. 6 and 8. Special washers 32, having one face curved and the other face plane, are provided. The curved faces fit the tubular stock and the plane faces abut. A pivot pin 26 passes through tubular stock, and washers, and is riveted over as indicated.

The diagonal braces 27 are of similar construction. Referring to Fig. 6, the diagonal brace 27 is suitably pivoted to the rail 16 and has a pin 28 adapted to fit in a hole in the leg 12. A slide 29 is mounted on screws 31 and has a seat 30 engaging over the brace 27 to hold the pin 28 in its hole.

The above construction permits folding the couch into a flat space, as indicated in Fig. 5. To set up the apparatus, it is only necessary to fold down the legs, as indicated in Fig. 1, place the pins 28 of braces 27 in their respective holes, and move the slides 29 to engage over the braces 27.

To use the apparatus, the patient merely lifts the lower foot rest 14, walks between extensions 17 to the foot of the couch and sits down. He then folds down the lower foot rest 14 and adjusts both the lower foot rest, and the upper foot rest 15 to proper position. He is then ready to take the three exercise positions illustrated in Figs. 2, 3 and 4.

Thus, convenient apparatus is provided for those who must take an exercise sometimes called the "Berger Exercise." This is as follows. The patient must lie on his back, with legs extended vertically above his trunk with his feet against the upper foot rest, for a given period of time (Fig. 2). He then sits up and allows his legs to hang over the edge of the couch while the feet and toes are articulated for a certain length of time (Fig. 4). The patient's legs dangle so that the feet do not touch the floor, and the patient may grasp the uprights. After this, the patient lies down with his legs stretched out horizontally and resting upon the lower foot rest (Fig. 3). The above cycle is then repeated. Other exercises requiring similar positions of the patient's body may be taken on this apparatus.

It will be noted that the spacing of the lower foot rest 14 from the foot of the couch top provides a lower passage through the frame of the couch; and that the spacing of the upper foot rest 15 at head height above the foot of the couch top provides an upper unobstructed passage through the frame of the couch. These two passages have decided advantages for the patient's comfort. The lower passage provides space through which the

patient's legs can dangle as in Fig. 4; it provides space through which the patient can raise his legs to rest them on the lower foot rest 14, as in Fig. 3. The upper passage provides space through which the patient may move his legs from the horizontal position of Fig. 3 to the up-raised position of Fig. 2. In addition, when lower foot rest 14 is raised, the lower and upper passages give the patient direct access to the foot of the couch top enabling him to sit down in the position shown in Fig. 4, without hindrance.

It will also be noted that the couch top 10, lower foot rest 14, upper foot rest 15 and upper and lower passages all lie in the same vertical plane so that the patient is free to move his body into the three main positions, shown in Figs. 2, 3 and 4, by simply swinging his legs or trunk, as the case may be, about horizontal axes adjacent his hips or knees, without any tiresome shifting, pivoting or twisting of his body.

The apparatus is simple to construction, easy to set up and use, and easily folded for storage. It has been found from actual experience that, when the upper foot rest is adjusted to accommodate the feet in upright position, it will clear the patient's head when sitting up. If it develops that some people sit higher so that their heads strike the upper foot rest, its center part can be cut away and the patient's feet rested on each side of the opening. The foot rests may, of course, be conveniently padded for the patient's comfort.

While certain novel features of the invention have been disclosed herein, and are pointed out in the annexed claims, it will be understood that various omissions, substitutions and changes may be made by those skilled in the art without departing from the spirit of the invention.

What is claimed is:

1. In an exercise couch, a framework comprising a couch top to support a patient's head and trunk in prone position, an upright standard at the foot end of said couch top, said standard comprising an upright on each side of the couch top, a foot rest comprising a rigid member bridging the upper portions of said uprights, said foot rest being vertically spaced from said couch top a distance corresponding to the patient's trunk and head to provide an unobstructed passage through the framework, the center lines of said couch top, said foot rest and passage lying generally in the same vertical plane, means to support said couch top above the floor a distance greater than the height of the patient's knees, whereby the patient may sit on the foot end of the couch with his hands grasping said uprights and with his legs projecting through said unobstructed passage and dangling over the end of the couch top, and whereby the patient may swing his trunk and head to prone position on the couch top and swing his legs through said unobstructed passage to a position against said foot rest, all without twisting his body.
2. In an exercise couch, a unitary framework comprising a couch top to support a patient's head and trunk in prone position, a lower foot rest on said framework at gen-

erally the same level as said couch top, said foot rest being horizontally spaced from the foot end of said couch top to provide a lower passage for the patient's legs through the framework between said couch top and foot rest, a generally vertical standard at the foot end of said couch top, an upper foot rest at the upper end of said standard, said upper foot rest being vertically spaced above said couch top a distance corresponding to the patient's trunk and head to provide an upper unobstructed passage through the framework for the patient's trunk, the center lines of said couch top, lower passage and lower foot rest and of said upper foot rest and upper passage lying generally in the same vertical plane, means to support said couch top above the floor a distance greater than the height of the patient's knees, whereby the patient may sit on the foot end of the couch with his legs dangling over the end of the couch top through said upper and lower passages, and whereby the patient may swing his trunk and head to prone position on the couch top and swing his legs through said lower passage to a position on said lower foot rest, and whereby said patient may swing his legs through said upper passage to a position against said upper foot rest, all without twisting his body.

3. A couch according to claim 2 in which the standard comprises an upright on each side of the couch top, which the patient may grasp when in sitting position with his legs dangling through said lower passage.

4. A couch according to claim 2 in which means are provided for moving said lower foot rest from its operative position to provide unobstructed access for the patient to the foot end of the couch top.

5. A couch according to claim 2 in which separate means are provided for adjusting the position of the lower and upper foot rests for patients of different height.

6. A couch according to claim 3 in which said couch top comprises side rails, said supporting means comprising first couch legs hingedly pivoted to the head end of the couch top at the inside of the rails and second couch legs hingedly pivoted at the foot end of the couch top at the outside of the rails, said uprights comprising extensions of said second couch legs, whereby, to fold the couch, said uprights may be folded down outside said rails and said first couch legs may be folded up inside of said rails.
